UNITED STATES PATENT OFFICE

WILLIAM F. GODFREY, OF KEARNEY, NEBRASKA

PUMP

Application filed May 1, 1930. Serial No. 448,836.

This invention relates to improvements in pumps.

The main object is to provide an improvement on the pump disclosed in my copending application filed December 14, 1929, and given Serial Number 413,988, the pump herein described being simpler in construction than the previous type and being provided with a packing means to prevent leakage of the liquid being pumped.

Another object is to provide a pump having its intake and outlet of greater effective size relative to the size of the pump as a whole, thereby increasing the efficiency and pumping capacity of the pump.

The foregoing and other objects together with means whereby the same may be carried into effect will best be understood from the following description of a preferred embodiment of the invention taken in connection with the accompanying drawings wherein:

Figure 1 is a side view of the improved pump, the same being partially broken away and shown in section.

Figure 2 is an enlarged horizontal section through the pump.

Figure 3 is an enlarged detail side view of one of the guide vanes.

In carrying out the present invention I provide an outer tubular or hollow casing 1 which is generally heart or heart cam shaped in plan and to the ends of which are fixed the upper and lower caps 2 and 3 by means of the bolts 4. An intake slot 5 is provided through the wall of the casing 1 and an exhaust slot 6 is also provided through the wall of the casing, the said slots being spaced apart and vertically elongated as shown. A housing 7 is provided around the exhaust slot 6, the same being closed at its lower end and extends above the top of the casing at its upper end. A cylindrical inner rotating casing or cylinder 8 is provided, the same being

smaller in diameter than the casing 1 but of somewhat greater length than the same. Circular recesses 9 are provided in the inner forces of the upper and lower caps 2 and 3 and conventional roller bearings 10 are mounted in these recesses 9. The ends of the

inner casing 8 are fixed in the inner races of the bearings 10 and this casing is thus journaled within the casing 1. It will be noted that this inner casing 8 is journaled concentrically with relation to the center of radii of the heart shaped outer casing 1 and is of such diameter that it contacts the inner face of said outer casing for a short distance at the point of shortest radius of this casing 1, this point being designated at 11 in Figure 2. The intake and exhaust slots 5 and 6 are disposed on each side of the point at which the inner and outer casings contact and this construction acts as an automatic check valve or block between the intake and exhaust as will be understood. By this means liquid entering the intake 5 must pass around the casing 8 before emerging from the exhaust 6. To further block the intake from the exhaust a vertically extended brush slot 12 is provided in the outer casing 1 between the slots 5 and 6 and an elongated brush 13 has its bristles 14 extended through this slot into engagement with the inner casing 8, the said brush being pressed in place by springs 15 braced between the said brush and a lip 16 extended from the side of the housing 7. This brush 13 may have its bristles 14 formed of any desired or suitable material such as wood fibres.

The inner casing 8 is provided with a centrally disposed depended stub shaft 17 which extends downwardly into a bearing housing 18 and rests upon a ball bearing 19, which bearing is adjustable in a vertical direction by means of threaded stud 20. A drive shaft 21 is secured to the upper end of the casing 8 and extends upwardly through the upper cap 2. This shaft 21 is then provided with a pulley 22 by means of which the casing 8 may be rotated by a suitable motor or engine (not shown).

Diametrically opposed and vertically extended slots 23 are provided in the inner casing 8 and a flat rectangular propeller or pumping blade 24 is slidably mounted through these slots as shown. This blade 24 is of just sufficient width to nicely fit within the outer casing 1 and since it is slidable in the inner casing 8 it may reciprocate therein

to follow the contour of the casing 1 as it rotates with the casing 8 as will be understood. The margins of the blade 24 are provided with wooden strips 25 to prevent wear 5 on the inner surface of the outer casing 1. Bearing housings 26 are provided within the casing 8 and a pair of spaced roller bearings 27 is mounted in each of these housings 26, the propeller blade 24 being slidably mounted 10 through the housings and between the bearings 27.

In operation the pump is seated in the well or other water supply and the inner casing 8 is rotated in the direction indicated by the 15 arrow in Figure 2 by a suitable engine or motor (not shown) belted to the pulley 22. The water will of course enter the casing 1 through the intake 5 and will then be forced out of the exhaust 6 by the revolving blade 20 24, the entrance of the water into the casing being furthered by the suction set up as the blade 24 rotates. A plurality of angularly set and cupped water deflectors or guide 25 vanes 28 are secured at intervals over the exhaust slot 6 and act to deflect the water ejected from that slot 6 upwardly in the housing 7 from which it may be piped or otherwise drawn off for use. For this reason the vanes 28 incline upwardly in the 30 direction of rotation of the casing 8 as shown. It will be apparent that the pump may be used for pumping other liquids such as oil or for pumping gases and the like. It will be noted that a larger space is left for the 35 intake and outlet of the water by the use of the heart shaped outer casing than is the case where the circular outer casing is used thus increasing the efficiency of the pump.

While I have herein set forth a certain preferred embodiment of my invention it is understood that I may vary from the same in minor structural details so as best to construct a practical device for the purposes intended, not departing from the spirit of the 45 invention and within the scope of the appended claims.

I claim:

1. In a device of the kind described, an outer elongated, vertically arranged hollow casing, heart shaped in plan, there being correspondingly elongated intake and exhaust slots formed longitudinally through the wall of the casing at either side of the longitudinal section thereof defining the inturned or obtuse portion thereof and there being a correspondingly elongated brush slot formed longitudinally through the wall of the casing immediately at the said inturned portion 50 thereof, end caps for the said outer casing, a correspondingly elongated, cylindrical inner casing of substantially less diameter than the outer casing, the same being rotatably mounted within the outer casing equally between the intake and exhaust slots thereof 55 and substantially in contact with the inner side of the said inturned portion thereof, the said inner casing being provided with diametrically opposed longitudinally extended blade slots formed through its walls, an elongated brush adjustably mounted through the said brush slot of the outer casing and adapted to bear upon the outer cylindrical surface of the inner casing, resilient means for maintaining the said brush in contact with the said inner casing, and a flat, rectangular pumping blade slidably mounted through the said blade slots of the inner casing, the outer edges of the blade having a 60 slideable contact with the inner surface of the outer casing.

2. In a device of the kind described, an outer elongated, vertically arranged hollow casing, heart shaped in plan, there being correspondingly elongated intake and exhaust 65 slots formed longitudinally through the wall of the casing at either side of the longitudinal section thereof defining the inturned or obtuse portion thereof and there being a correspondingly elongated brush slot formed longitudinally through the wall of the casing immediately at the said inturned portion thereof, end caps for the said outer casing, a correspondingly elongated, cylindrical inner 70 casing of substantially less diameter than the outer casing, the same being rotatably mounted within the outer casing equally between the intake and exhaust slots thereof and substantially in contact with the inner side of the said inturned portion thereof, the said inner casing being provided with diametrically opposed longitudinally extended blade slots formed through its walls, an elongated brush adjustably mounted through the said brush slot of the outer casing and adapted to bear upon the outer cylindrical surface of the inner casing, resilient means for maintaining the said brush in contact with the said inner casing, and a flat, rectangular pumping blade slidably mounted through the said blade slots of the inner casing, the outer edges of the blade having a slideable contact with the inner surface of the outer casing.

3. In a device of the kind described, an outer elongated, vertically arranged hollow casing, heart shaped in plan, there being correspondingly elongated intake and exhaust slots formed longitudinally through the wall of the casing at either side of the longitudinal section thereof defining the inturned or obtuse portion thereof and there being a correspondingly elongated brush slot formed longitudinally through the wall of the casing immediately at the said inturned portion thereof, end caps for the said outer casing, a correspondingly elongated, cylindrical inner 90 casing of substantially less diameter than the outer casing, the same being rotatably mounted within the outer casing equally between the intake and exhaust slots thereof and substantially in contact with the inner side of the said inturned portion thereof, the said inner casing being provided with diametrically opposed longitudinally extended blade slots formed through its walls, an elongated brush adjustably mounted through the said brush slot of the outer casing and adapted to bear upon the outer cylindrical surface of the inner casing, resilient means for maintaining the said brush in contact with the said inner casing, and a flat, rectangular pumping blade slidably mounted through the said blade slots of the inner casing, the outer edges of the blade having a slideable contact with the inner surface of the outer casing.

In testimony whereof I affix my signature.

WILLIAM F. GODFREY.
